UNITED STATES PATENT OFFICE.

JAMES E. SMITH, OF ATLANTIC CITY, NEW JERSEY.

TRAIN-STOPPING APPARATUS.

1,146,110.

Specification of Letters Patent. Patented July 13, 1915.

Application filed September 18, 1914. Serial No. 862,385.

To all whom it may concern:

Be it known that I, JAMES E. SMITH, a citizen of the United States, residing at Atlantic City, in the county of Atlantic and State of New Jersey, have invented new and useful Improvements in Train-Stopping Apparatus, of which the following is a specification.

This invention relates to improvements in train stopping apparatus and has particular application to mechanically controlled apparatus of this character.

In carrying out the present invention, it is my purpose to provide automatic train stopping apparatus whereby the propelling power of the locomotive or motor car will be cut off and the brakes applied in the event of the car or train entering the danger zone.

It is also my purpose to provide apparatus of the class described which will embrace the desired features of simplicity, efficiency and durability, which will operate effectively under all conditions and wherein the component parts will be so arranged and correlated as to reduce the possibility of derangement to a minimum.

With the above and other objects in view, the invention consists in the construction, combination and arrangement of parts hereinafter set forth in and falling within the scope of the claim.

In the accompanying drawings, Figure 1 is a fragmentary sectional view through a locomotive showing the car carried mechanism. Fig. 2 is a plan view of the motor controlling mechanism removed from the locomotive. Fig. 3 is a fragmentary transverse sectional view through the mechanism illustrated in Fig. 2. Fig. 4 is a fragmentary perspective view of a detail of such mechanism. Fig. 5 is a fragmentary transverse sectional view through the trackway showing one of the signal controlled obstacles. Fig. 6 is a fragmentary top plan view of the trackway showing the obstacles in top plan. Fig. 7 is a fragmentary sectional view through the obstacles.

Referring now to the drawings in detail, 1 designates a locomotive which, in the present instance, is of the steam driven type, while 2 and 3 indicate, respectively, the throttle valve lever and engineer's brake valve handle.

Arranged within the locomotive cab is a motor comprising, in this instance, a vertical tubular casing 4 having a closed lower

end and an open upper end and designed to contain a quantity of water 5 or other fluid. Within the receptacle 4 and normally held adjacent to the upper end thereof by the fluid therein is a float 6 having the under surface equipped with a depending shock absorbing device, 7.

8 designates a cable trained over a guide sheave 9 suspended from the roof of the cab and having the lower end of one run connected with a weight 10 disposed within the upper end of the tubular casing 4 immediately above the upper surface of the float 6 and the lower end of the remaining run connected with tripping mechanism 11 suspended from the floor of the cab and holding the cable 8 normally taut and the weight 10 out of contact with the float 6. Connected with the throttle lever 2 and the engineer's brake valve handle 3 respectively are cables 12 and 13 trained over suitable guide sheaves 14 arranged within the cab and having the free ends thereof connected with a loop 15 carried by the weight 10. By means of this construction, it will be seen that when the tripping mechanism 11 is actuated to release the lower end of the particular run of the cable 8 the weight 10 will gravitate toward the bottom of the casing 4 thereby exerting a pull upon the cables 12 and 13 with the effect to close the throttle valve and actuate the engineer's brake valve to effect an application of the brakes. In the downward movement of the weight 10 the float 6 descends and as the float reaches the lower end of its path of movement the shock absorbing device 7 engages the bottom wall of the tank thereby eliminating shock jar to the mechanism.

The tripping mechanism 11 is suspended from the floor of the cab of the locomotive and comprises pairs of brackets 15, 16, the brackets of each pair being spaced apart from each other transversely of the locomotive and from the brackets of the other pair longitudinally of the locomotive. Suitably fastened to and interconnecting the lower ends of the brackets of each pair 15 and 16 is a cross bar 17 and fastened to the bottom edges of the cross bar 17 and extending longitudinally of the locomotive is supporting rod 18. Suitably fastened to the lower extremities of the bracket 15 are coiled springs 18' extending toward the front end of the locomotive parallel with the rod 18 and terminating to one side of the transvers-

center line of such rod, while secured to the lower extremities of the bracket 16 and projecting rearwardly therefrom are coiled springs 19 lying parallel with the rod 18 and terminating a short distance from the adjacent ends of the springs 18'. Connected with the front ends of the springs 18' and extending transversely of the bar 18 is a metallic strip 20 having the lower edge resting upon the bar 18, while fastened to the rear ends of the springs 19 is a metal strip 21 spaced apart from the strip 20 and lying parallel therewith and having the lower edge thereof resting upon the bar 18. Passed through alining openings in the strips 21 adjacent to the upper edges thereof is a pin 22 passed through an eye 23 in the lower end of the cable 8, the pin 22 and the eye 23 cooperating to hold the cable 8 taut and so prevent downward movement of the weight 10 of the motor. Resting upon the bar 18 between the confronting surfaces of the metallic strips 20, 21 and having the opposite extremities thereof projecting beyond the sides of the locomotive is a trip bar 24.

Arranged along the trackway at suitable intervals are obstacles 25 connected through suitable operating mechanism 26 with the signal blades of the respective semaphores so that when the signal blades go to danger the obstacles will be operated to active position, that is to a position in the path of movement of the trip bar 24, while when the signals are in clear position, the obstacles will be inactive or out of the path of movement of the trip bar.

In practice, when a signal blade is at danger and the associated obstacle active, the bar 24 on a train running by the danger signal will impact against the active obstacle, thereby swinging the bar 24 so that the same will come into contact with one or the other of the metal strips 20, 21 according to the direction of travel of the locomotive. As the trip bar engages the particular metal strip 20, 21, such strip is moved

longitudinally along the bar 18 against the action of the particular set of springs 18', 19, with the effect to disengage the pin 22 and so release the cable 8 of the influence of the pin whereby the weight 10 may gravitate to lowered position as previously described. When the pin 22 is relieved of the influence of the strip 21, incident to the forward movement of such strip or the rearward movement of the strip 20, the pin 22 swings upwardly within the opening in the strip 20 and the eye 23 slides off of the pin under the action of the weight.

From the foregoing description taken in connection with the accompanying drawings, the construction, mode of operation and manner of employing my invention will be readily apparent.

It will be seen that I have provided train stopping apparatus whereby the propelling power of the motor car will be cut off and the brakes applied in the event of such car running by a danger signal and wherein the weight motor will be operated independently of the direction of travel of the car.

I claim:

In train stopping apparatus, the combination with a controlling element of the motor car, a motor for operating said element to cut off position, a cable having one end connected to said motor and the opposite end depending through the floor of the car, an eye on the lower end of said cable, a pin passed through said eye, strips carrying said pin and holding the latter, springs holding said strips in normal position, and a trip bar between said strips and capable of swinging movement to engage one or the other of the strips to release said pin and cable so that the motor may operate.

In testimony whereof I affix my signature in presence of two witnesses.

JAMES E. SMITH.

Witnesses:

MARY SMITH,
CHRISTOPHER SMITH.
